[57] CLAIM

The ornamental design for a hexagonal plug, as shown and described.

DESCRIPTION

FIG. 1 is a front view of the hexagonal plug showing the new design;

FIG. 2 is a perspective view from above and the right side thereof;

FIG. 3 is a bottom view thereof;

FIG. 4 is a rear view thereof;

FIG. 5 is a side view from the right side thereof;

FIG. 6 is the same view as FIG. 1 but with a shorter tail;

FIG. 7 is the same view as FIG. 2 but with a shorter tail;

FIG. 8 is the same view as FIG. 3 but with a shorter tail;

FIG. 9 is the same view as FIG. 5 but with a shorter tail; and

FIG. 10 is the same view as FIG. 5 but with a shorter tail. The broken line showing throughout the drawing figures is included only for the purpose of illustrating the article in which the design is embodied and forms no part of the claimed design.
